UNITED STATES PATENT OFFICE

149,764

DESIGN FOR A COMBINED MOTOR AND BLOWER BASE AND VACUUM CLEANER COVER

Clarence W. Lanter, Bartlett, Ill., assignor to
Breuer Electric Mfg. Company, Chicago, Ill., a
corporation of Illinois

Application November 29, 1946, Serial No. 135,165

Term of patent 14 years

(Cl. D9—2)

To all whom it may concern:

Be it known that I, Clarence W. Lanter, a citizen of the United States, residing at Bartlett, in the county of Du Page and State of Illinois, have invented a new, original, and ornamental Design for a Combined Motor and Blower Base and Vacuum Cleaner Cover, of which the following is a specification, reference being had to the accompanying drawings, forming part thereof.

Fig. 1 is a top plan view of a combined motor and blower base and vacuum cleaner cover, showing my new design.

Fig. 2 is a side elevational view of same.

Fig. 3 is a sectional view taken along the line 3—3 of Fig. 1.

Fig. 4 is a rear elevational view showing the combined motor and blower base and vacuum cleaner cover.

Fig. 5 is a front elevational view of same.

Fig. 6 is a sectional view taken along the line 6—6 of Fig. 1.

I claim:

The ornamental design for a combined motor and blower base and vacuum cleaner cover, substantially as shown.

CLARENCE W. LANTER.
